(No Model.)

E. B. PUTNEY.
BILL FILE.

No. 476,487.

Patented June 7, 1892.

UNITED STATES PATENT OFFICE.

EDWIN B. PUTNEY, OF LYONS, NEW YORK.

BILL-FILE.

SPECIFICATION forming part of Letters Patent No. 476,487, dated June 7, 1892.

Application filed January 21, 1892. Serial No. 418,762. (No model.)

To all whom it may concern:

Be it known that I, EDWIN B. PUTNEY, of Lyons, in the county of Wayne, in the State of New York, have invented new and useful 5 Improvements in Bill-Files, of which the following, taken in connection with the accompanying drawings, is a full, clear, and exact description.

My invention relates to bill-files.

10 My object is to produce a bill-file or letter-file so constructed and arranged that it may be used as a petty ledger, provided with ledger-marked sheet upon which the items may be readily drawn direct from the blotter or day-book or journal and then taken out or torn off and forwarded as statements which shall contain an itemized account, and at the same time forming a convenient method for keeping small accounts without the necessity of opening 15 regular ledger accounts.

My invention consists, first, in providing means for holding in tablet form sheets of paper ruled in ledger form or otherwise, as desired; second, in providing for holding them 20 singly or in sets; third, in providing means for readily turning to any account by the index at the side; fourth, in providing means for separating the sheets which are turned up; fifth, in providing means for holding them 25 there, and in the several other novel features of construction and operation hereinafter described, and specifically set forth in the claims hereto annexed.

Figure 1 is an isometrical elevation of my 30 bill-file complete open. Fig. 2 is a side elevation of the file closed. Fig. 3 is a top plan view of the upper end with the rest removed. Fig. 4 is a side view of the hinged joint detached, enlarged, and partly open, showing the 35 position which they take when the bill-file is open. Fig. 5 is a view of a single hinge detached, showing a section of a set of leaves secured to the base-piece upon which the ear forming part of the hinge is mounted on line 40 xx , Fig. 3. Fig. 6 is a section on line yy , Fig. 3, the strap released at one end.

A is the base-piece, upon which the ledger-leaves or bill-leaves 1, arranged, preferably, alphabetically, are mounted, the leaves or 45 sheets of each letter or set of letters being secured to a base-piece 2, which is provided with a side piece 3 and upward-extending

ears 4 at their ends, as shown, and adapted to be secured together loosely, thereby forming hinge-joints. These sheets are secured to the 55 base-piece 2, preferably by perforating them and inserting them over a post or rivet 5 and erected in the base-piece 2, and are held down in engagement therewith by a spring-strap 6, hinged to one side of the file, as at a , and 60 adapted to be held at its opposite end by inserting it under the loop 7. I preferably index the leaves upon the side in the ordinary way.

8 is an L-shaped bracket, constructed, preferably, of wire and hinged to the front or top end of the base A and adapted to be thrown over on its base, when it is desired to open the file or turn to any account, thereby forming a support for the parts which have been turned 70 over, as shown in Fig. 1.

9 is a loop or bracket secured substantially central to the base or to pieces secured loosely to the base and adapted to be thrown down, as shown in Fig. 2, and raised to the position 75 shown in Fig. 1, when it is desired to hold the file open for the purpose of inspecting any account.

The inner end of one or both sides of the bracket is constructed with a crank-arm, and 80 an indentation is made in the base, which is provided with a strap-spring and so arranged that the crank-arm will engage with it when in the raised position, the object of which is to produce a tension upon the leaves when in 85 the position shown in Fig. 1 and to hold it in an inclined position when down, as shown in Fig. 2.

Having described my invention, what I 90 claim is—

1. In a bill-file, the combination, with the base 2, having ears thereon, of the sheets of paper removably secured to said base, said bases being adapted to be loosely connected together through their ears, as set forth. 95

2. In a bill-file, the combination, with the bases 2, having ears thereon, of sheets of paper removably secured to said bases and having an index upon their margins. 95

3. The combination, with the bases 2, having ears thereon and adapted to be loosely connected together, of sheets of paper removably secured to said base, and the whole mounted upon a base 4, as set forth. 100

4. The combination, with the bases 2, of the sheets secured thereon, said bases 2 being loosely secured together and mounted upon the base A, of a bracket mounted upon the front end of the base A for the purpose of forming a rest when the sheets are turned up, and the bracket 9, mounted upon the base A for the purpose of holding the sheets up, as set forth.
5. The combination, with the bases 2, having ears thereon and provided with vertical studs, sheets of paper perforated to fit over said studs, said bases being adapted to be

loosely secured together at their ears, and the whole mounted upon the base A, of the brackets 8 and 9, the bracket 9 being provided upon its inner end with a crank-arm and adapted to engage with the strap-spring upon the outer edge of the base, with which the crank-arm engages, as set forth.

In witness whereof I have hereunto set my hand this 13th day of January, 1892.

EDWIN B. PUTNEY.

In presence of—
H. P. DENISON,
C. W. SMITH.
